(57) **CLAIM**

The ornamental design for a case for electronic communications device, as shown and described.

DESCRIPTION

FIG. 1 is a front, right-side, and top perspective view of a case for electronic communications device showing my new design;

FIG. 2 is a rear, left-side, and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The interior of the case shown in FIGS. 1 and 3 and the broken lines throughout the drawing figures form no part of the claimed design. The broken lines and regions bounded by broken lines depict portions of the case for electronic communications device that form no part of the claimed design.
